UNITED STATES PATENT OFFICE.

EDWIN J. DUKES, OF NEW YORK, N. Y., ASSIGNOR TO AIKEN-LAMBERT CO., OF NEW YORK, N. Y.

DESIGN FOR A PENCIL.

47,643.

Specification for Design.

Patented July 27, 1915.

Application filed March 20, 1915. Serial No. 15,965. Term of patent 14 years.

To all whom it may concern:

Be it known that I, EDWIN J. DUKES, a citizen of the United States, and a resident of the city of New York, borough of Brooklyn, in the county of Kings and State of New York, have invented a new, original, and ornamental Design for a Pencil, of which the following is a specification, reference being had to the accompanying drawing, forming part thereof.

The figure is a side view of a pencil illustrating my new design.

I claim:

The ornamental design for a pencil, as shown.

EDWIN J. DUKES.

Witnesses:

WILLIAM I. FERRIS,
THOMAS J. DUKES.
